UNITED STATES PATENT OFFICE

EVELYN N. HOLLAND, OF PROVIDENCE, RHODE ISLAND, ASSIGNOR TO C. G. KING & CO.,
INC., OF PROVIDENCE, RHODE ISLAND

DESIGN FOR A BICENTENNIAL BADGE

Application filed December 30, 1931. Serial No. 42,302. Term of patent 3½ years.

To all whom it may concern:

Be it known that I, EVELYN N. HOLLAND, a citizen of the United States, residing at Providence, in the county of Providence and State of Rhode Island, have invented a new, original, and ornamental Design for Bi-Centennial Badge, of which the following is a specification, reference being had to the accompanying drawings, forming part thereof.

In said drawings, Fig. 1 is a front face view,

and Fig. 2 is an edge view of a bi-centennial badge, showing my new design.

I claim:

The ornamental design for a bi-centennial badge as shown.

Signed at Providence, in the county of Providence and State of Rhode Island, this 28th day of December, A. D. 1931.

EVELYN N. HOLLAND.
